HIS ATTORNEY

UNITED STATES PATENT OFFICE.

WESLEY N. ONDERDONK, OF SYRACUSE, NEW YORK, ASSIGNOR TO REMINGTON TYPE-WRITER COMPANY, OF ILION, NEW YORK, A CORPORATION OF NEW YORK.

TYPE-WRITING MACHINE.

1,216,838.

Specification of Letters Patent. Patented Feb. 20, 1917.

Application filed May 3, 1915. Serial No. 25,464.

To all whom it may concern:

Be it known that I, WESLEY N. ONDERDONK, citizen of the United States, and resident of Syracuse, in the county of Onondaga and State of New York, have invented 5 certain new and useful Improvements in Type-Writing Machines, of which the following is a specification.

My invention relates to typewriting machines and it has for its principal object to provide an improved means for arresting the return stroke of the space bar or space key of the typewriter in such manner as to prevent vibration or rebound of said space 10 bar or space key. In certain forms of the Monarch typewriter the space bar has been disconnected from the universal bar and from the ribbon vibrator mechanism and operates only the dog rocker of the carriage 15 escapement, the load on the space bar being thus reduced. It has been found that if the said bar was quickly depressed and released, it rebounded from the stop that limited its upward motion and vibrated to a certain 20 extent and sometimes to a sufficient extent to cause skipping of the escapement. To remedy this trouble was the immediate and specific occasion of the making of this invention.

To the above ends my invention consists 25 in certain features of construction and combinations and arrangements of parts, all of which will be fully set forth herein and particularly pointed out in the claims.

In the accompanying drawings,

Figure 1 is a fore-and-aft vertical section of enough of a Monarch typewriter to illustrate the embodiment of my invention in that machine.

Fig. 2 is an isometric view of a stop forming part of my invention.

Fig. 3 is an irregular vertical section through said stop.

Fig. 4 is a fragmentary section like part 45 of Fig. 1 but illustrating a modification.

Fig. 5 is a fragmentary, diagrammatic view in section like part of Fig. 1 and showing the same form of the invention as Fig. 1 but showing the space bar in its depressed 50 position.

Fig. 6 is a bottom view of the machine, but with many parts omitted.

Figs. 2 and 3 are on a larger scale than the other figures of the drawings.

The main frame of the Monarch type- 55 writer comprises a base 1, corner posts 2 and a top plate 3, from which last rise standards 4, supporting stationary carriage rails 5, which, through the intervention of rollers 6, support a carriage 7 having a platen 8 60 mounted therein. Front strike type bars 10 are pivoted on a segment 11 and carry types adapted to strike against the front face of the platen 8, and said type bars are operated by links 12 and sub-levers 13 which latter 65 are pivoted on printing key levers 14 and coöperate at their lower ends with a fulcrum rod 15. The key levers are mounted to rock on a fulcrum plate 16, and they all overlie a universal bar 17, which is mounted on 70 arms 18 rigid with a rock shaft 20 mounted in the base of the machine. The universal bar frame, in addition to the universal bar 17, arms 18 and rock shaft 20, comprises, near the middle thereof, an arm 21 which is 75 connected by a link 22 with an operating lever 23 pivoted on the underside of the top plate 3 and at its forward end controlling the ribbon vibrator 24. The ribbon spools, not shown, are driven by a shaft 25 having 80 thereon certain devices 26 which control the action of the ribbon vibrator in a manner which it is not necessary to go into here but which is well known in the art. The arm 21 has a forwardly directed part between 85 which and a stationary bracket 27 there is compressed a restoring spring 28 for the universal bar. Said bracket 27 is omitted in Fig. 6 to avoid confusion in the drawing.

In the Monarch machine as at one time 90 constructed the carriage escapement was controlled by an extension of the arm 21. In the present instance, however, the motion of said arm 21 is not communicated directly to the escapement but said arm has a 95 lever 30 pivoted thereto at one side thereof at 31, and said lever has a slot 32 which is engaged by a pin 33 projecting from the arm 21 in such fashion that said pin normally occupies the lower part of said slot so that 100 if the universal bar be depressed said pin will cause the lever 30 to be rocked with the universal bar about the axis of the shaft 20; but the lever 30 can itself be rocked about the pivot 31 without disturbing the arm 21 105 or the universal bar. At its rear end the lever 30 has pivoted thereto at 34 the lower end of a link 35 which is retained on its

pivot by a flat spring 35^a. The upper end of the link 35 is pivoted at 36 to the dog rocker 37 which dog rocker is controlled by the usual restoring spring 38. Said dog rocker carries the usual or any suitable feed dogs 40 engaging in any suitable manner with the usual escapement rack or wheel 41, which wheel is mounted on the rear end of a shaft having on its forward end the feed 5 pinion 42 that meshes with the feed rack 43, which feed rack is carried by the carriage 7 in the usual way. It is the spring 38 that normally holds up the rear end of the lever 30 whereby the pin 33 occupies the lower 10 part of the slot 32.

The space bar 44 is mounted on the forward ends of two levers 45 which are fulcrumed on a certain transverse shaft 46 in the base 1 of the typewriter. In the Monarch machine this shaft 46 is the rock shaft 20 of the segment shift mechanism, most of which mechanism is omitted from the present drawings. Said shaft has thereon, as parts of the shift mechanism, certain arms 25 which, in Fig. 6, are shown broken away. The levers 45 extend a short distance to the rear of the shaft 46 where they are engaged by wire restoring springs 47, secured by screws 48 to a cross bar of the base 1. The 30 two levers 45 near their rear ends are rigidly connected by a cross rod 49 and near the middle thereof said rod has a rearwardly projecting arm 50 which is rigidly connected with the rod by means of a pin 51 passing 35 through the rod and through the hub of the arm. The arm 50 has an adjusting screw 52 threaded upward therethrough and having a lock nut. Said screw at its upper end is adapted to engage the underside of 40 a lip or ear 53 bent off from the forward arm of the lever 30. The construction is such that if the space bar 44 be depressed the screw 52 will press upward on the ear 53 and rock the lever 30 about its pivot 31 and 45 thus operate the escapement without operating the universal bar or the ribbon vibrator.

In the Monarch machine there are usually provided two stops 54 to limit the downward motion of the space bar, one of these stops 50 being mounted near each end of said bar. These stops are shown in Fig. 6, but omitted elsewhere for clearness.

The coöperating stop devices whereby the return stroke of the space bar is arrested, 55 comprise a lug 55 cast integral with the front bar 56 of the base 1, said lug having an inclined face 57, preferably machined. The other coöperating stop member comprises a felt pad 58 mounted on a sheet metal 60 arm 60 suitably secured to the under side of the space bar 44 and set at an inclination corresponding to that of the surface 57. In the specific embodiment of the invention here shown the arm 60 is a T-shaped piece 65 of sheet metal secured to the under side of

the space bar by means of two screws 61, Fig. 5, passing through holes 62 in said T-shaped arm. The depending branch of the arm 60 springs from the rear of the cross part and is curved downward and forward 70 in the manner shown in the drawings, and extending forward beyond the space bar to position for coöperation with the stationary stop 55, the lower part of said arm 60 preferably being bent at such an angle as to 75 bring the piece of felt 58 flat against the surface 57. Said piece of felt may be secured in any suitable way to the arm 60. As here shown said arm is perforated and a cord or wire 63 is passed through the felt and 80 through the perforations and is drawn down tight and the two ends of the wire or cord are then twisted or tied together as indicated in Fig. 3. The arm 60 is of such material and dimensions as to have a little elasticity, and it is also capable of being adjusted by bending.

It will, of course, be understood that these precise details of construction can be varied to a considerable extent. For example, 90 in Fig. 4, I have shown a sheet metal stop 64 secured to the bar 56 by means of screws or rivets 65 and bent so that its rear surface occupies an angle similar to that of the surface 57 in the other form of the invention. 95

The coöperating stop surfaces heretofore employed in this situation have been substantially horizontal and when they came into contact on a quick up-stroke of the bar, said bar was likely to rebound. According 100 to my invention the coöperating stop surfaces are inclined in such a way that the pressure between them is not directly up and down but is more nearly radial of the arc in which the space bar moves than tangential of said arc, so that at each impact between the parts 55 and 58 there is a cramping or wedging of the space bar mount or frame toward the rod 46.

In Fig. 5 the dotted line 66 is an arc 110 struck about the axis of the rod 46 as a center and 67 is a line tangent to said arc where said arc meets the stop surface 57. 68 is a line drawn in the plane of and as a sort of continuation of said stop surface 57. It will 115 be noted that the line 68 and the stop surface 57 are at an inclination to the tangent 67, which tangent represents the direction of motion of the movable stop at the moment when it comes into contact with the stationary stop. It will be noted that this inclination is at an acute angle. This angle should not be so fine or small as to produce such a wedging action as to cause a noticeable resistance to the next operation of the 120 space bar. On the other hand, this angle should not be so coarse or wide as to allow of the objectionable rebound which it is the purpose of my invention to prevent or to so far reduce as to render it of no consequence. 130

The angle shown in the drawings is one that I have found to be good and an angle of about such as that shown is in fact the angle that I prefer to use; but said angle 5 can be varied to some extent without sacrificing the advantages of the invention. In the present instance the angle between the lines 67 and 68 is approximately 30°.

Various changes can be made in the details of construction and arrangement without departing from my invention.

What I claim as new and desire to secure by Letters Patent, is:—

1. The combination with a main frame including a transverse front bar, of a space bar, a stop secured to and depending from the under side of said space bar and having its contact surface extending downward at a forward inclination, and a coöperating stop on said transverse frame bar having its stop surface facing backward at a downward inclination whereby on the upstroke of said space bar the movable stop engages the stationary stop at an inclination to the path of said movable stop so as to arrest said space bar without rebound.
2. The combination with a main frame and a depressible space bar, of a stationary stop on the main frame facing backward at a downward inclination, and a coöperating stop secured to the under side of said space bar and consisting of a dependent, resilient arm extending downward at a forward inclination into position to contact with said stationary stop and having its stop surface facing forward at an upward inclination whereby on the return or upstroke of said space bar the movable stop engages the stationary stop at an inclination to the path of said movable stop so as to arrest said space bar without rebound.

Signed at Syracuse, in the county of Onondaga, and State of New York, this 30th day of April, A. D. 1915.

WESLEY N. ONDERDONK.
